UNITED STATES PATENT OFFICE

CHARLES R. BLOOD AND HUBERT J. HUMBERT, OF SACRAMENTO, CALIFORNIA

MACHINE FOR PLANING THE SURFACES OF PAVEMENTS

Application filed October 24, 1929. Serial No. 402,202.

This invention relates to machines for planing the surfaces of pavements, and has for its object the provision of a planer for the purpose intended, comprising a rotary cutting head or cutter being arranged and adapted to 5 or planing head mounted at the lower end of a vertical shaft driven by power from a suitable motor, and carried by a traveling frame, mounted on traction wheels, such planing head or cutter being arranged and adapted to 10 be moved transversely of its supporting frame, to and fro, while the frame is traveling on its wheels, or remaining stationary, and being also arranged and adapted to be raised or lowered as required, as well as adjusted to operate on horizontal or inclined 15 surfaces.

The invention is embodied in a machine to be hereinafter specifically described, and consists in the novel construction and combination of elements constituting such machine, and as set forth in the claims.

In the accompanying drawings which illustrate a preferred embodiment of the invention,

25 Figure 1 is a front elevation of the machine;
Figure 2 is a plan view;
Figure 3 is an end elevation; and
Figure 4 is a vertical sectional view of the 30 cutting or planing head.

The frame of the machine is designated generally by the numeral 4 and comprises a pair of horizontal flanged beams mounted on traction wheels 5, having shafts or axles 22. 35 The latter have their bearings in vertically adjustable blocks 26, which are carried by the frame and are vertically adjustable by means of the screws 25 and hand wheels 24.

40 One pair of the wheels 5 is positively driven from a suitable motor 6 mounted on the frame, through the sprocket wheels 20, 18, 14 and sprocket chains 16 and 21, and may be thrown into and out of engagement with the driving mechanism by clutch mechanism 45 23.

The sprocket wheel 14 is carried by the motor shaft, upon the inner end of which is mounted a sprocket wheel 14', which is coupled to a sprocket wheel 9 on a horizontal shaft 7, mounted on the frame 4. The shaft

7 carries also a sprocket wheel 10, which is thrown into and out of engagement with the shaft by means of suitable manually operable clutch mechanism 13. A gear wheel 9' on shaft 7 engages with a pinion 9² and through the same rotates a transverse screw shaft 11, to which the pinion 9² is keyed. This shaft has its bearings in the frame beams 4, and passes through one side of a block 11' arranged and adapted to move 55 across the frame between the flanges of the I-beams 17' forming part of the frame of the machine.

Through the opposite side of the block 11', a shaft 18 extends and is parallel to the shaft 11. The shaft 18 has splined thereon a worm 18' collared on both ends and located in a recess in block 11' sliding in key ways on shaft 18. This worm meshes with a worm wheel 18² mounted on the vertical shaft 18³ 60 upon the lower end of which is fitted the planer head 17. When the shaft 7 is in clutch engagement with the gears 9' and 9², the latter drives the shaft 11, and through the screw thread on the latter moves the block 11' and with it the planer head 17 in one 65 direction.

When however the clutch 12 is disconnected from the gear 9', and the clutch 13 brought into engagement with the sprocket 10, the shaft 11 will be rotated in an opposite direction and the travel of the block 11' and planer head 17 reversed, from which it will be seen that the planer head is movable in two directions over the surface of the pavement or 70 plane to be operated on.

The planer head 17 consists of a cylindrical block having cutting or planing blades 17" fastened in place in radial kerfs in the periphery of the head.

As will be seen, the shaft 18 is driven from the motor by means of the sprocket chain 16 and the sprocket wheels 14 and 15, and the planing head rotated on its axis at any position through the engagement of the worm 85 18' and worm wheel 18².

I claim:—

1. A machine of the character described comprising a main frame mounted on traction wheels, a driving motor carried by said 90

frame, driving connections between the motor and traction wheels, a planing head carried by said frame and mounted for horizontal rotation on a vertical shaft, a member in which said shaft rotates, and which is arranged and adapted to be moved crosswise of the frame in opposite directions, and connections between the motor, the said shaft and its supporting member, for rotating said planing head and propelling it crosswise of said frame, said connections including a vertical shaft on which the planing head is mounted and to which is keyed a worm wheel; a pair of parallel shafts, one of which is a screw shaft engaging with and moving said supporting member, a worm splined on the other shaft and arranged and adapted to operate said vertical shaft and to move crosswise of the frame in constant engagement with said worm wheel.

2. A machine as claimed in claim 1, and comprising means for vertically adjusting the frame.

3. A machine as claimed in claim 1, and provided with means for controlling the movement of the planing head and its supports transversely in opposite directions.

4. A machine as claimed in claim 1, provided with manually operable clutch mechanism whereby the traction wheels may be thrown into and out of driving engagement with the motor.

5. A machine as claimed in claim 1, provided with manually controllable means for engaging and disengaging the motor with and from the member by which the planing head is carried.

6. A machine of the character described, comprising a supporting frame, traction wheels on which said frame is supported, a horizontally rotating planing head, a vertical shaft on which the latter is mounted, a member in which said shaft is journaled, a worm wheel keyed to said vertical shaft, a horizontal shaft, a worm slidably mounted on and splined to said shaft, a horizontal worm shaft in engagement with the member in which the vertical shaft is journaled and arranged and adapted to move said member to a direct line crosswise of the frame, guide beams on which said member travels, a motor mounted on said frame, and driving connection between the said motor and the said horizontal shafts.

7. In testimony whereof we affix our signatures.

CHARLES R. BLOOD.
HUBERT J. HUMBERT.
